PISTON PACKING

Einar K. Johansen, Chicago, Ill., assignor to
Clearing Machine Corporation, Clearing, Ill., a
corporation of Illinois

Application March 27, 1940, Serial No. 326,256

3 Claims. (Cl. 309—34)

This invention relates to improvements in piston packing and one of the objects of the same is to provide in a packing of this character improved means for holding the packing material against the cylinder wall.

A further object is to provide an improved packing of this character which will be of a simple, durable and compact construction, readily applicable as well as readily removable, and which will be effective and efficient in operation.

To the attainment of these ends and the accomplishment of other new and useful objects as will appear, the invention consists in the features of novelty in substantially the construction, combination and arrangement of the several parts hereinafter more fully described and claimed and shown in the accompanying drawing, illustrating this invention, and in which

Figure 1 is a sectional view of a piston having a packing constructed in accordance with the principles of this invention applied thereto.

Figure 2 is a detail perspective view of the cup shaped member of the packing.

Figure 3 is an end elevation of another element of the packing.

Figure 4 is a perspective view of still another one of the packing elements.

Referring more particularly to the drawing and in the preferred form of the invention, the numeral 10 designates a piston which is reciprocable in a cylinder, the numeral 11 indicating the cylinder wall. One face of the piston is preferably cut away, to form a circumferential recess opening through the periphery and also one face of the piston.

The numeral 13 designates a cup shaped packing element preferably constructed of any suitable material, preferably of leather, and is provided with an opening 14 in the bottom thereof.

This element 13 is seated within the recess 12 and is of a diameter that the peripheral wall 15 thereof will contact the cylinder wall 11 and when in position will rest against the bottom of the recess in the piston.

The numeral 16 designates another one of the elements of the packing and this element is formed of any desired or suitable material, preferably elastic material such as rubber, and is normally of a disc shaped formation and of any desired or suitable thickness. The diameter of the element 16 is somewhat greater than the internal diameter of the cup shaped member 13 and is adapted to be forced into the cup shaped member so that it will contact with the bottom of the latter. When the element 16 is forced into

the cup shaped member the peripheral edge thereof or for a substantial distance radially of the element will be deflected as shown in Figure 1 so that when the body of the element contacts the bottom of the cup shaped member the deflected peripheral portion of the element 16 will contact the inner wall of the cup shaped member 13.

The numeral 17 designates a retainer member which may be constructed of any suitable material and of any desired thickness, the periphery thereof being preferably formed on an arc which extends in a direction lengthwise of the axis of the member 17 so as to provide a rounded periphery 18. The greatest diameter of the retainer member 17 is slightly greater than the actual, or theoretical inside diameter of the deflected portion of the element 16 so that when the retainer member 17, which in the present form of the invention is provided with a central opening 19, is forced into the element 16, it will clamp the element 16 between the retainer 17 and the cup shaped member 13. The parts are held in this assembled relation by means of suitable fastening bolts or screws 20 that pass through openings 21 in the retainer 17, which are preferably countersunk, through openings 22 in the element 16, openings 23 in the cup shaped member 13, and into the piston 10.

When this retainer member is forced into the cup shaped formation resulting from forcing the element 16 into the cup shaped member 13 and as the diameter of the retainer member 17 is greater than the internal diameter in the formation of the element 16, the area 24 of the deflected portion of the element 16 will be compressed between the peripheral wall 18 of the cup shaped element 13 that engages the cylinder wall 11 and the periphery of the retainer 17. This will result in holding the peripheral wall 18 of the element 13 against the cylinder wall without the use of springs.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. In combination, a piston operable in a cylinder, said piston having a circumferential recess opening through the end and periphery thereof, an annular cup shaped flexible member seated in said recess and encompassing a portion of the piston, a second annular and nor-

mally substantially flat flexible member of a diameter considerably greater than the inside diameter of the cup shaped member and adapted to be seated in said recess, and encompassing a portion of the piston, a substantially flat rigid annular retaining member encompassing a portion of said piston and contacting the said second annular member, said retainer member being of a diameter less than the diameter of the last said annular member and also of the cup shaped member, and fastening members passing through all of said members and engaging the piston whereby to draw said retainer and the said normally flat annular member into the cup shaped member to deflect the periphery of the said normally flat annular member, the diameter of said retainer member being greater than the normal inside diameter of the deflected portion of the second said member, whereby said deflected portion of the latter will be compressed to hold the wall of the cup shaped member against the cylinder wall.

2. In combination, a piston operable in a cylinder, said piston having a circumferential recess opening through the end and periphery thereof, an annular cup shaped flexible member seated in said recess and encompassing a portion of the piston, a second annular and normally substantially flat flexible member of a diameter considerably greater than the inside diameter of the cup shaped member and adapted to be seated in said recess, to encompass a portion of said piston and to normally contact the edge of the wall of the cup shaped member, a substantially flat rigid annular retaining member encompassing a portion of said piston and contacting the said second annular member, said retainer member being of a diameter less than the diameter of the last said annular member and also of the cup shaped member, and fastening members passing through all of said members and engaging the piston whereby to draw said retainer and the said normally flat annular member into

5 the cup shaped member to deflect the periphery of the said normally flat annular member, the diameter of said retainer member being greater than the normal inside diameter of the deflected portion of the second said member, whereby said deflected portion of the latter will be compressed to hold the wall of the cup shaped member against the cylinder wall.

10 3. In combination a piston operable in a cylinder, said piston having a circumferential recess opening through the end and periphery thereof, an annular cup shaped flexible member seated in said recess and encompassing a portion of the piston, a second annular and normally substantially flat flexible member of a diameter considerably greater than the inside diameter of the cup shaped member and adapted to be seated in said recess, and encompassing a portion of the piston, a substantially flat rigid annular retaining member 15 encompassing a portion of said piston and contacting the said second annular member, said retainer member being of a diameter less than the diameter of the last said annular member and also of the cup shaped member, and fastening members passing through all of said members and engaging the piston whereby to draw said retainer and the said normally flat annular member into the cup shaped member to deflect the periphery of the said normally flat 20 annular member, the diameter of said retainer member being greater than the normal inside diameter of the deflected portion of the second said member, whereby said deflected portion of the latter will be compressed to hold the wall of the cup shaped member against the cylinder wall, the periphery of the said retainer member being continuous and formed on an arc extending in a direction lengthwise of the axis of the retainer member, whereby the portion of the second said member that is compressed will be 25 spaced from the edge of the deflected portion thereof.

EINAR K. JOHANSEN.
